A. V. CHAPIN

AUXILIARY AIR AND FUME SUPPLY FOR EXPLOSIVE ENGINES

Original Filed Oct. 4, 1924.

Inventor

Alfred V. Chapin,

By Samuel Henriet,

Attorney

UNITED STATES PATENT OFFICE.

ALFRED V. CHAPIN, OF SAN ANTONIO, TEXAS.

AUXILIARY AIR AND FUME SUPPLY FOR EXPLOSIVE ENGINES.

Original application filed October 4, 1924, Serial No. 741,669. Divided and this application filed June 15, 1925. Serial No. 37,235.

This invention relates to an automatically controllable auxiliary air inlet mechanism for the intake manifold of internal combustion engines. This application is a division 5 of my co-pending application Serial Number 741,669.

In the accompanying drawings:

Fig. 1 is a view of an intake manifold, partly in section, showing the auxiliary 10 valve connected to move in unison with the throttle valve.

Fig. 2 is a view like Fig. 1 but with the auxiliary valve in the nature of a spring controlled check valve.

Fig. 3 is a sectional view of a manifold and associated parts with the auxiliary valve controlled by a governor.

Fig. 4 is a sectional view of an intake manifold illustrating a structure wherein the 20 movement of an auxiliary inlet valve for air is in accordance with the thermal conditions prevailing.

Like numerals designate corresponding parts in all of the figures of the drawing.

Referring to the drawing 5 designates an intake manifold and 6 the connection to the usual carburetor of an internal combustion engine, said carburetor not being shown.

An auxiliary supply pipe, 7 leads to the 30 manifold 5 and it may conduct only heated air or it may conduct an auxiliary fuel charge. In either case an auxiliary air inlet valve 8, in Figs. 1, 2 and 3, serves to control a port 9 for the admission of atmospheric air to the pipe 7. The valve 8 is operable manually by means of the handle 10.

In Fig. 4 the valve 8^a corresponds to the valve 8 in the other figures but in this case said valve is actuated by means of links 11

40 and 12 and expandible element 13 located in the intake manifold 5. Thus the movement of the valve 8^a is determined by the heat of the fuel mixture passing through the manifold. If this fuel mixture becomes unduly

45 warm the valve 8^a will open to admit an auxiliary supply of air through port 9^a. In Fig. 1, 14, designates the main controlling valve of pipe 7. This valve is actuated through a crank arm 15 and spring 16 in

50 unison with the main throttle valve 17 of the engine, said throttle valve being operable by a rod 18. A second rod or wire 19, controllable from the dash of the vehicle,

is provided with a pin 20. One end of the

spring 16 is attached to this pin and the other end of said spring is attached to the crank arm 15. Thus by shifting the rod 19 the tension of spring 16 may be varied and this in turn will determine the degree of movement of valve 14 in unison with the throttle valve 17.

In the form of the invention, illustrated in Fig. 2, the main controlling valve 14^a, corresponding in function to the valve 14, is spring actuated to closed position after the manner of a check valve by means of a spring 22.

In the form of the invention, illustrated in Fig. 3, the main controlling valve 14^b is controlled as to its movement by means of a governor of conventional form, indicated at 14^c, the valve opening as the engine's speed increases.

In the form of the invention illustrated in Fig. 4, a governor 24 acts to vary the tension of a spring 25, one end of which is connected to a lever 26. A spring 27 connects the lever with the actuating rod 18 of the throttle valve 17. However, in this case the movement of the lever 26 acts to vary the tension of the actuating spring 22^a of the auxiliary main valve 14^a.

It is to be understood that the invention is not limited to the precise constructions set forth but that it includes, within its purview, whatever changes fairly come within either the terms or the spirit of the appended claim.

Having described my invention what I claim is:

The combination with the intake manifold of an internal combustion engine, of a carburetor connection leading thereto, a throttle valve in said connection, an auxiliary pipe leading from a side of said manifold in advance of the throttle valve, which pipe serves to conduct a fluid other than atmospheric air to the manifold, an auxiliary air inlet port in said pipe for the admission of atmospheric air of dilution thereto, a manually operable controlling valve for said port and a main valve in the auxiliary pipe, between the auxiliary air inlet valve and the manifold, controllable with the throttle valve.

In testimony whereof he affixes his signature.

ALFRED V. CHAPIN.
